(57) **CLAIM**

The ornamental design for a flat bottomed shoe sole with a false arch bridge, as shown and described.

DESCRIPTION

FIG. 1 is a perspective view of a flat bottomed shoe sole with a false arch bridge for a left shoe showing my new design; FIG. 2 is a front view of the flat bottomed shoe sole with a false arch bridge for a left shoe;

FIG. 3 is a rear view of the flat bottomed shoe sole with a false arch bridge for a left shoe;

FIG. 4 is a top view of the flat bottomed shoe sole with a false arch bridge for a left shoe;

FIG. 5 is a right side view of the flat bottomed shoe sole with a false arch bridge for a left shoe;

FIG. 6 is a left side view of the flat bottomed shoe sole with a false arch bridge for a left shoe;

FIG. 7 is a bottom view of the flat bottomed shoe sole with a false arch bridge for a left shoe;

FIG. 8 is a perspective view of a second embodiment of the flat bottomed shoe sole with a false arch bridge for a right shoe showing my new design;

FIG. 9 is a front view of the flat bottomed shoe sole with a false arch bridge for a right shoe;

FIG. 10 is a rear view of the flat bottomed shoe sole with a false arch bridge for a right shoe;

FIG. 11 is a top view of the flat bottomed shoe sole with a false arch bridge for a right shoe;

FIG. 12 is a right side view of the flat bottomed shoe sole with a false arch bridge for a right shoe;

FIG. 13 is a left side view of the flat bottomed shoe sole with a false arch bridge for a right shoe; and,

FIG. 14 is a bottom view of the flat bottomed shoe sole with a false arch bridge for a right shoe.

The broken lines depict unclaimed environmental subject matter.
